UNITED STATES PATENT OFFICE.

WILLIAM S. SEYMOUR, OF PHILADELPHIA, PENNSYLVANIA, ASSIGNOR TO
ELMER H. GREY, OF SAME PLACE.

WOVEN-WIRE MATTRESS.

SPECIFICATION forming part of Letters Patent No. 446,193, dated February 10, 1891.

Application filed November 24, 1888. Serial No. 291,745. (No model.)

To all whom it may concern:

Be it known that I, WILLIAM S. SEYMOUR, a citizen of the United States, residing in the city of Philadelphia, county of Philadelphia,

5 State of Pennsylvania, have invented certain new and useful Improvements in Woven-Wire Mattresses, of which the following is a specification.

In Letters Patent of the United States 10 granted to me September 10, 1889, No. 410,937, and which in part constitute a division hereof, is shown and claimed a woven-wire mattress made up of an upper and a lower woven-wire fabric with intermediate springs, whose 15 terminal coils are connected thereto in such a way that the tendency of said coils to expand keeps the fabric taut. The preferred means for attaining the desired result is shown to be through the instrumentality of 20 parallel "extra" wire cables intertwined with the fabric and arranged at a distance from each other less than the diameter of the said terminal coils, so that by compressing the top and bottom coils of each spring and running 25 said coils through two adjacent wire cables each cable is maintained at a uniform distance from the adjacent parallel cable, the cables are kept in position below the surface of the woven-wire fabric, and the fabric presents 30 a uniform outer surface, which is maintained taut by reason of the tendency of the compressed terminal coils to expand.

The present invention is embodied in a construction possessing the same features of 35 advantage, with the additional characteristic that the woven-wire fabric is carried around and joined at its ends, so as to inclose or envelope the assemblage of springs at top, bottom, and sides. By "sides" I mean

40 those portions of the mattress between its top and bottom edges where the folding of the fabric takes place. I employ the term generically, as it is evident that the same invention is present whether the fabric envelopes 45 the assemblage of springs in the direction shown in the drawings or in a direction transverse thereto.

My invention comprises, broadly, an assemblage of perpendicular springs and a woven-

wire fabric which is carried around them at 5° top, bottom, and sides, the terminal coils of the springs engaging with the fabric at top and bottom.

In the accompanying drawings, Figure 1 represents a spring bed-bottom or mattress 55 embodying my invention. Fig. 2 represents a plan view of a portion of the same, and Fig. 3 represents a section taken on the line G G of Fig. 2.

Similar letters of reference indicate similar 60 parts throughout the several views.

As shown in the drawings, the mattress or bed-bottom consists of a woven-wire fabric A, forming its top and bottom and connected by intermediate perpendicular spiral springs B, 65 as shown, said fabric being carried over the sides of the assemblage of springs and joined at its ends, so as to encompass the same.

The mattress is, for convenience, made in two sections, so as to be readily shipped or 70 stored. The springs are connected at their opposite ends to the fabric by means of the extra or auxiliary wires or cables F, intertwined within the coils of the fabric. The upper and lower loops or terminal coils E of 75 the springs B are first compressed and in the compressed condition inserted between adjacent cables. The tendency of the said coils or loops to expand stretches the fabric, and at the same time the extra wire cables F are 80 drawn in, so as to leave the surface of the woven-wire fabric without any projecting obstruction. It will be evident that with the construction shown the spring bed-bottom or mattress will be reversible, so that either surface 85 may be uppermost when the mattress is in use.

What I claim is—

A woven-wire mattress consisting of an assemblage of perpendicular springs and a 90 woven-wire fabric covering the top, bottom, and sides of said springs, the terminal coils of the springs engaging with the fabric at top and bottom, substantially as described.

WILLIAM S. SEYMOUR.
